US0D1094623S

(12) **United States Design Patent** (10) Patent No.: **US D1,094,623 S**
(45) Date of Patent: ** Sep. 23, 2025

(54) **WEAPON LIGHT**

(71) Applicant: **Crimson Trace Corporation**,
Columbia, MO (US)

(72) Inventors: **Tim Meissen**, Columbia, MO (US);
William A. Planck, Columbia, MO
(US); **Shane Ball**, Columbia, MO (US);
William Garland, Columbia, MO (US);
Michael Cottrell, Ashland, MO (US);
James Tayon, Moberly, MO (US);
Ryan Donahue, Columbia, MO (US);
John Oller, Columbia, MO (US)

(73) Assignee: **Crimson Trace Corporation**,
Columbia, MO (US)

(**) Term: **15 Years**

(21) Appl. No.: **29/791,095**

(22) Filed: **Dec. 29, 2021**

(51) LOC (15) Cl. 22-01
(52) U.S. Cl.

USPC **D22/108**

(58) **Field of Classification Search**

USPC D8/394; D14/418; D22/108, 109, 110,
D22/199; D21/567; D26/60

CPC F41G 1/32; F41G 1/345; F41G 11/003
